UNITED STATES PATENT OFFICE.

WILLIAM BODETTE, OF TOLEDO, OHIO.

DIPPER-TOOTH.

No. 820,906.

Specification of Letters Patent.

Patented May 15, 1906.

Application filed February 20, 1906. Serial No. 302,138.

To all whom it may concern:

Be it known that I, WILLIAM BODETTE, a citizen of the United States, residing at Toledo, in the county of Lucas and State of Ohio, have invented new and useful Improvements in Dipper-Teeth, of which the following is a specification.

This invention relates to dipper-teeth for steam-shovels and the like, the object of the invention being to provide a strong, durable, and effective dipper-tooth and means whereby said tooth may be readily and quickly detached from the dipper or shovel and reapplied thereto, thus facilitating repairs.

With the above and other objects in view the invention consists in the novel construction, combination, and arrangement of parts hereinafter fully described, illustrated, and claimed.

In the accompanying drawings, Figure 1 is a side elevation of a dipper-tooth embodying the present invention shown applied to a dipper or shovel, the latter being in section. Fig. 2 is a vertical longitudinal section through the tooth and contiguous portion of the dipper or shovel. Fig. 3 is a plan view of the tooth, showing a portion of the shovel in dotted lines. Fig. 4 is a detail perspective view of one of the saddle-plates, and Fig. 5 is a similar view of one of the bifurcated portions of the dipper-tooth.

Referring to the drawings, 1 designates the main body of the improved dipper-tooth, and 2 the working point thereof, the same being of any usual or preferred form.

In carrying out the present invention the rear portion of the body of the tooth is slotted, as shown at 3, thereby forming what may be termed "upper" and "lower" bifurcated portions 4 and 5, respectively, the same being located at a distance from each other equal to or slightly greater than the thickness of the edge portion of the dipper or shovel. (Shown at 6.) The bifurcated portions 4 and 5 are made of unequal length, the upper portion 4 being of greater length than the lower portion 5. The upper bifurcated portion 4 is provided at its rear end with a rabbeted tongue 7, and the lower bifurcated portion 5 is provided with a corresponding rabbeted tongue 8. Each tongue, as shown in Fig. 5, is of less width than the bifurcated portion from which it projects, and for about one-half the length of said tongue the latter is recessed or rabbeted, as shown at 9, thus forming an abrupt transverse shoulder 10.

By reference to Figs. 1 and 2 it will be noted that the rabbets of the tongues 7 and 8 are reversely disposed, or, in other words, the rabbets are formed in the outer surfaces of 60 the tongues.

In connection with the rabbeted tongues hereinabove described I use a pair of saddle-plates, 11 designating the upper saddle-plate, and 12 the lower saddle-plate. Each of said 65 saddle-plates is recessed or rabbeted, as shown at 13, the formation of the rabbet corresponding in every particular with the formation of the rabbeted tongue associated therewith, so that when the tongue and saddle-plate are 70 brought together they interlock and form a splice or scarf-joint, as will be readily understood by an inspection of Figs. 4 and 5. Coupling-bolts 14 are inserted transversely 75 and horizontally through the overlapping and interlocking portions of the joint, thus anchoring the tooth to the saddle-plates, the saddle-plates being in turn permanently fastened to the top and bottom of the dipper or shovel 6 by means of rivets 15 or their equivalent.

The dipper or shovel 6 is provided at a suitable point with an offset 16, forming upper and lower shoulders 17 and 18, and the top and bottom saddle-plates 11 and 12 are 85 recessed, as shown at 19, to form corresponding shoulders 20, which bear against the shoulders on the dipper or shovel and assist in maintaining a firm and rigid relation between the saddle-plates and the dipper or 90 shovel.

21 designates a fastening-bolt which passes vertically through the dipper-tooth and edge portion of the dipper or shovel.

The dipper-tooth, which is preferably 95 formed of manganese steel, is easily applied to and removed from the dipper or shovel by removing the bolt 21 and also taking out the bolts 14. The scarf-joints between the bifurcated portions of the tooth and the saddle-plates 100 form a secure and reliable anchorage for the tooth and prevent throwing undue strain on the connecting or fastening bolts. The construction described also prevents the jamming or buckling of the bolts, and thus 105 by keeping the bolts in good condition the removal of the same is greatly facilitated.

The invention is shown and described in its preferred embodiment herein; but it is to be understood that I do not limit myself to the 110 exact arrangement disclosed, but reserve the right to make such changes in the form, pro-

portion, and minor details of construction as may suggest themselves without sacrificing any of the principles or advantages thereof.

I claim—

- 5 1. A dipper-tooth comprising upper and lower bifurcated portions having their extremities rabbeted, in combination with rabbeted saddle-plates.
- 10 2. A dipper-tooth comprising rearwardly-extending bifurcated portions, and saddle-plates with which said bifurcated portions have an interlocked engagement.
- 15 3. A dipper-tooth comprising bifurcated portions, and saddle-plates having a scarf-jointed connection with said bifurcated portions.
- 20 4. A dipper-tooth comprising bifurcated portions terminating in tongues, and saddle-plates recessed to receive said tongues.
- 25 5. A dipper-tooth comprising bifurcated portions having terminal tongues, saddle-plates recessed to receive said tongues, and

fasteners passing through the tongues and saddle-plates.

6. A dipper-tooth comprising rearwardly-extending bifurcated portions, saddle-plates with which said bifurcated portions have an interlocked connection, and dipper-engaging shoulders on said saddle-plates. 25

7. A dipper-tooth comprising rearwardly-extending bifurcated portions adapted to straddle the dipper, saddle-plates secured to the dipper and having an interlocked engagement with the bifurcated portions of the tooth, and a bolt passing through the bifurcated portions of the tooth and also through the dipper. 30

In testimony whereof I affix my signature in presence of two witnesses.

WILLIAM BODETTE.
